CLAIM

The ornamental design for a pet collar, as shown and described.

DESCRIPTION

FIG. 1 is a perspective view of a pet collar including a base layer and a decorative outer layer attached thereto by VELCRO;

FIG. 2 is a front view of the pet collar of FIG. 1;

FIG. 3 is a rear view of the pet collar of FIG. 1;

FIG. 4 is a side view of the pet collar of FIG. 1;

FIG. 5 is an opposite side view of the pet collar of FIG. 1;

FIG. 6 is a top view of the pet collar of FIG. 1; and,

FIG. 7 is an exploded perspective view of the pet collar of FIG. 1, showing the base layer, the decorative outer layer, and the VELCRO, for ease of illustration.

The broken line elements, including all depictions of stitching, are not claimed.

Portions of the collar which are not shown from behind the unclaimed buckle form no part of the claimed design.
